MULTIPLE-SOCKET ELECTRIC PLUG.

Application filed April 18, 1925. Serial No. 24,086.

In charging batteries for radio and other work by a charging machine coupled with an electric light circuit, it is frequently desirable to employ an electric lamp as a resistance to cut down the current to the charging machine, and thus prevent the machine over-charging the battery. The object of this invention is to provide a two-way plug socket adapted to be mounted in the usual household 5 socket and carry an electric lamp and the plug of the battery charging machine in series with each other. When such a device is employed, no current can flow through the battery charger unless the lamp is in place, so that 10 the lamp acts not only to reduce the current to the charger, but also as a telltale, showing by its illumination that the current is flowing.

We carry out the above object by arranging the terminal shells and center contacts in 15 our multiple socket in series with the lead-in conductors, and we provide a construction which permits the device to be cheaply formed and readily assembled.

Preferred forms for carrying out our invention are illustrated in the drawings where- 20 in Fig. 1 is a front elevation of a double ended barrel socket of the pin type made in accordance with our invention; Fig. 2 is a section taken on a plane indicated by the line 2—2 in Fig 1; Fig 3 is a longitudinal section taken 25 vertically through the device shown in Fig. 1; Fig. 4 is a perspective view of one of the connecting pieces employed in the socket of Figs 1, 2 and 3.

Our invention is shown in connection with 30 a casing comprising electrical insulating material such as Bakelite which is molded to the desired shape. The casing illustrated in Figs. 1, 2 and 3 has opposite and outwardly 35 facing openings 11 and 12 in the nature of pockets which are separated by a wall 13. The casing also has passageways 14 and 15 which lead outwardly from the openings 11 and 12 respectively, and has passageways 25 and 29 which extend through the wall 13 and 40 provide communication between the pockets.

Electric current may be brought into the casing through contact blades 16 and 17 which may frictionally engage the usual 45 screw threaded plug indicated in broken lines in Figs. 1 and 3. These blades are shown as extending into the passageways 14 and 15 respectively and are connected at their inner ends to the central contact pieces 20 and 21.

The central contact member 20 forms one 55 terminal connection while a threaded shell 22 in the pocket 11 forms a cooperating terminal connection for receiving a plug or lamp in the usual way. In the socket 12 is a similar threaded shell 23 which cooperates with the 60 contact member 21. The two shells are electrically connected together and thus the current passes through them in series.

To connect the shells 22 and 23, we have 65 shown a metallic strip 24 which extends through a passageway 25 in the casing and projects into each pocket where it is engaged by the respective shells. By corrugating the strip, as at 26 and 27, we insure a firm electrical connection with the sockets when the 70 binding screws 18 and 19 are threaded onto the blades 16 and 17 respectively.

The current flowing into one of the conductors as at 16, passes through center contacts 20, and then through a current reducing 75 device, as a lamp in the shell 22, then through shell 22, connector 24, shell 23, then through a battery charger or other translating device having its plug in the shell 23, to central contact 21 and out through conductor 17. Thus 80 current will not flow unless both sockets are occupied, as intended.

It will be seen from inspection of Fig. 3 85 that the metal shells are effectively retained in their respective sockets by insulating washers 50 which overlie inturned flanges of the shells at their bases. A washer 51 is likewise placed beneath each shell flange. The screw 90 of the central contact clamps these two washers together so that they thus clamp the shell flange between them. The inner washers, particularly in Fig. 3, prevent the shell flanges contacting with the leading-in bars.

In the form shown, it will be seen that 95 two shells are electrically connected together, while the two central contacts form terminals of the two leading-in members. This makes a simple construction and one which may be readily assembled. It will be evident from the description given that we have provided 100 an electric fixture embodied in a two-way plug-socket which may be inserted between the terminal plug of the battery charging outfit and any electric socket, and serve as a protector and indicator.

Having thus described our invention, we 105 claim:

In a device of the character described, the

combination of a barrel having a pair of aligned pockets, a pair of contact blades extending laterally through the wall of the barrel into the interior adjacent the base of the 5 pockets, metallic screw shells in the pockets respectively, central metallic contacts connected to the blades respectively and operating through insulation to hold the shells in place, and a metallic strip lying along the

inner surface of the barrel and contacting 10 with the two shells whereby the sockets are connected together in series with the two contact blades.

In testimony whereof, we hereunto affix our signatures.

ISAAC F. GILES.
JACK A. ROBERTS.
